The ornamental design for a lawn mower, as shown and described.

DESCRIPTION

FIG. 1 is a front perspective view of a lawn mower, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is the plan view of its folded state;

FIG. 10 is the plan view of its folded state;

FIG. 11 is its folded state diagram;

FIG. 12 is a partial enlarged view of FIG. 1; and,

FIG. 13 is a partial enlarged view of FIG. 1.

The broken lines in the drawings illustrate the portions of the lawn mower, which form no part of the claimed design. The large scale dash-dot broken lines on FIGS. 1, 12 and 13 define the enlargement regions in each and form no part of the claimed design.
